REED FOR LOOMS

Waldo H. Fish, Central Falls, R. I.

Application April 26, 1930, Serial No. 447,637

1 Claim. (Cl. 139—192)

This invention relates to improvements in reeds for use in looms, slashers or other textile machines of the type particularly adapted to silk looms.

5 The primary object of this invention, is to provide a reed for weaving looms which is more simple in construction than the present day reed and which is also more economical to manufacture.

10 A further object of this invention, is to provide a reed for weaving looms having better characteristics than the present day all-metal weaving reed and which provides more resiliency in the dents.

15 A still further object of this invention, is to provide a device of the above mentioned character adapted to prevent breakage of the dents due to the acid which adheres thereto during the construction of the reed.

20 Heretofore, it has been common practice to form weaving loom reeds of all-metal construction consisting in holding the ends of the dents together by solder. It has also been common practice in pitch bar reeds to space the ends of

25 reed dents by means of pitch covered string coiled around wooden ribs which also serves to hold the dents in their rigid spaced relation relative to the reed frame or end bars.

The above practice is objectionable, due to the 30 fact that in the first instance, above set forth, the acid or flux seeps down between the dents on the operative faces thereof and causes the dents to rust and become broken at a point adjacent the frame. The second instance above 35 named, is objectionable due to the fact that the reed heretofore formed with pitch covered strings are so resilient that they are not adapted to the finer weaves but are suitable only for coarser fabrics.

40 The above objects and disadvantages, are overcome by providing or forming a weaving loom reed by first spacing and retaining the dents to the side ribs by means of pitch covered strings and then dipping the ends of the dents which 45 extend a distance beyond the side ribs into a bath of molten solder whereby the same are rigidly held in place relative to the frame and to each other. Should solder flux or acid still remain on the ends of the reed dents, after the same have 50 been secured, the same will not sink down to the operative spaces of the reed dents to cause the same to deteriorate or otherwise become broken, due to the fact that the pitch covered strings 55 intercept any acid or solder flux and retains the same or restricts the same directly to the ends

of the reed dents as will be more fully described.

Other objects and advantages of the invention, will become apparent during the course of the following description, forming a part of this specification and in which,

5 Figure 1 is a perspective view, partly broken away of an embodiment of this invention;

Figure 2 is a perspective view of the same showing the rectangular frame pieces moved and the ends of the dents extending beyond the side 10 ribs and the pitch covered string windings;

Figure 3 is a transverse sectional view showing the ends of the reed soldered together relative to each other and to the side or rectangular frame pieces and showing the pitch covered 15 strings which intercept the solder from the operative faces of the reed dents;

Figure 4 is a front enlarged elevational view 20 partly in section showing the steps of winding the reed to the side ribs with pitch covered twine; and

Figure 5 is a front elevational view partly in section showing the device enlarged and in its assembled relation.

25 For a consideration of a detailed description of the invention, attention is directed to the several figures of the drawing, wherein the reference character 5 will generally be employed to designate the metallic end pieces which are common to all weaving loom reed constructions. Secured to the end metallic pieces 5 is a pair of opposite ribs 6 which is also common to present day weaving all metal loom reeds. In the construction illustrated in the several figures of the drawing, the reed dents 7, having been placed in their 30 respective positions by a reed setting machine which automatically winds the reeds with the pitch covered string 9, are then first spaced in the usual manner by metallic spring spacers after 35 which the dents 7 are in a position shown in Figure 4, wherein the ends of the dents 8 are shown extending above the side ribs 6. In the present construction, the ends 8 extend unusually 40 further than the present day construction for a purpose which will be described hereinafter.

45 The dents 7, having been placed in their respective positions by a reed setting machine which automatically winds the reeds with the pitch covered string 9, are thus held to the ribs 6 in their spaced relation. The reed is thus set up into the desired shape and size and the dents 7 spaced to 50 their desired positions.

55 The dents 7 having been placed in position and secured by the tar covered twine 9, the frame pieces 10 are placed over the ends 8 and held in

position by temporary fastenings or clips, after which the ends 8 of the dents 7 are dipped into a flux or soldering acid and then dipped into a molten bath of solder, whereby the solder adheres to the ends 8 of the dents and holds the same in a rigid spaced relation, also serving to hold the side frame members 10 in position, as illustrated in Figure 1. Figure 3 also illustrates the solder 11 between the dents 7 at the ends 8 thereof and shows the manner of securing the side frame pieces 10 in position whereby the weaving reed is completed.

It will readily be observed that any soldering acid or soldering flux which does not become removed during the soldering operation will not moisten the reed dents 7 by capillary attraction, as the pitch covered twine 9 intercepts any such acids or flux from passing from the ends 8 to the operative portion of the dents 7. This method of forming weaving loom reeds produces a reed in which the dents 7 have more resiliency than the all-metal reeds now in common use and it also forms a weaving loom reed which will last a considerable length of time, due to the fact that the

same is free from deterioration at the junctures of the dents 7 and the pitch covered twine 9.

It is to be understood, that the form of invention herein shown and described is to be taken as a preferred embodiment of the same and that various changes in the size, shape and arrangement of parts may be resorted to without departing from the spirit of the invention or the scope of the subjoined claim.

Having thus described the invention, what is claimed is:—

A loom reed comprising dents accurately spaced at equal predetermined distances from each other, means rigidly joining the ends of said dents together and resilient dam means interposed between each dent inside of said rigid joining means, comprising resilient pitch impregnated cord wound around metal ribs on each side of said dents near each end thereof with a coil between each dent, whereby said dam means may prevent the soldering acid or flux from attacking the dents in use.
